F. SOENNECKEN, OF BONN-ON-THE-RHINE, GERMANY.

COPYING-MACHINE.

1,184,223.

Specification of Letters Patent. Patented May 23, 1916.

Application filed November 25, 1913. Serial No. 803,000.

To all whom it may concern:

Be it known that I, RICHARD BERGER, a subject of the King of Bavaria, and residing at Venusbergstrasse 23, Bonn-on-the-Rhine, 5 in Germany, have invented certain new and useful Improvements in Copying-Machines.

This invention relates to an arrangement for bringing auxiliary mechanisms of copying machines, such as the cutting device, 10 feed and stamping devices and so forth, into operation through the intervention of the copying paper drawn off a roll, the control of the auxiliary mechanisms by the copying paper being such as to cause the starting and 15 stopping of any of the said mechanisms to be dependent on the movement of the copying paper and in accordance with actual requirements. For this purpose a feeler or equivalent device is provided which comes 20 into operation with varying sizes of papers for copying, the actuating of the feeler not being dependent on a predetermined number of revolutions of a part of the machine, say the copying roller, but being dependent 25 on the length of the sheets.

In order to use the copying paper from a storage roll for actuating the feeler, the former is provided with marks or perforations, at suitable distances apart, into or 30 with which the feeler can engage. The thin copying paper is not strong enough to transmit a more or less great force. This difficulty is overcome by causing the copying paper, with which the feeler is in contact without producing any appreciable effort thereon, to impart a slight motion to the feeler of such a nature as to require no effort on the part of the copying paper. For example, gravitation can be utilized so that 35 the first slight motion of the feeler causes the latter to be coupled direct or through intervening parts with the mechanism to be set in motion by the copying machine, while at the same time the feeler is allowed 40 or caused to return to its initial position.

The improvement is shown in the annexed drawings, in which:

Figure 1 is a side elevation of a copying machine; Fig. 2, a detached part thereof; 50 Fig. 3 a detail and Fig. 4 a perspective view of the copying paper in connection with the controlling mechanism.

The copying-strip 1, drawn off the roller 2, passes over a roller 3 through the water bath 4 to the copying rollers 5, 6 and 7. The 55

driving movement is imparted to the roller 7 and when the latter is pressed in the known manner against the roller 6 rotation is transmitted by friction to the rollers 5 and 6.

Between the table 8 and the paper 1 there 60 is a constantly revolving shaft 9 and a parallel shaft 10 is driven through the intervention of gear wheels 9¹ and 10¹ (Fig. 2).

On the shaft 9 is fast a grooved friction wheel 11, and on the shaft 10 is mounted a 65 loose wedge-shaped wheel 12 formed with a peripheral recess 13 which in the position shown in Fig. 1 interrupts the connection between these wheels. The wheel 12 is held in this position through the intervention of 70 a feeler-arm 14 on the sleeve 12¹ of said wheel 12 (Figs. 2 and 4.) The feeler rests upon the paper 1 in the path of perforations 15 therein. When a perforation advances beneath the feeler, the latter enters same and so 75 causes the wheel 12 to turn until its wedge-shaped circumference engages in the groove of the wheel 11 and is then rotated by the latter. The wheel 12 turns until it is again in the position shown in Fig. 1 when the 80 feeler 14 comes to rest on the surface of the paper, until it subsequently drops into another perforation.

At one end of the shaft 10 is fixed a 85 chain wheel 16 which by a chain is connected with a chain wheel 17 loose on the shaft 18. (Fig. 1). A further chain-drive 20 imparts motion in the known manner to a wheel 19 loose on the shaft of the copying roller 7. From here another chain-drive 20¹ 90 passes to the roller 21.

The chain wheel 17, loose on the shaft 18, is connected with a grooved wheel 22 (Fig. 3). On the shaft 18 is fixed an arm 23 which carries a short cranked shaft 24 with coupling 95 member 25 at one side and with the cranked portion 26 in the path of a bent arm 27, 28 of which the arm 28 is controlled by a bell-crank lever 29, 30 (Fig. 1). The arm 30 is controlled by a feeler 14 on the shaft 10. 100

On the shaft 18 is a spring-clip or sweeper 31 which at the rotation of the shaft 18 carries the original documents from the table 8 to the copying rollers (Figs. 1 and 3). 105

When the feeler 14 drops into a perforation 15 of the copying paper, and the loose wheel 12 is taken around by the constantly rotating grooved wheel 11 in the manner previously explained the feeler-arm 14 110

causes the bellcrank 29, 30 to swing and to swing also the bent arm 27, 28 thereby freeing the crank 26 of shaft 24 from the arm 27 (Fig. 3). The wedge-shaped coupling member 25 now comes in engagement with the wheel 22. The arm 23 is taken around with the grooved wheel 22 and takes the shaft 18 with it. The shaft 18 lets the feed device 31 make one revolution and this motion may be utilized to set in motion any other auxiliary mechanism of the machine. When the crank 26 comes in contact with the bent arm 27, which meanwhile has returned to its initial position, the coupling-wedge 25 in the grooved wheel 22 will be disengaged and the parts come to rest till the feeler 14 enters the next following perforation 15.

20 The distance between the perforations is the controlling factor for the intermittent operation of the auxiliary mechanisms of the copying machine, and the timing to suit different sizes of documents for copying is insured when for each one a copying roll 25 with corresponding perforations is placed in the machine.

With the previously described arrangement, the intermediate device 12, 14, after being started by the copying paper, receives 30 its real motion from the machine and serves only for disengaging the stopping device 27 of the auxiliary mechanism.

I claim:

1. The combination with a copying machine including cutting, feeding, and stamping devices and copying paper, of a shaft located above the copying paper, a finger on the shaft adapted to engage a perforation in the paper, means for causing a rotation 40 of the finger after said engagement, and means operated by the finger during its rotation for starting the operation of the aforesaid devices.

2. The combination with a copying machine including cutting, feeding and stamping devices and copying paper, of a shaft located above the paper, an interrupted gear mounted loosely on the shaft, a finger mounted for rotation with the gear, a constantly driven shaft adjacent the first mentioned shaft, a gear fixed on the second shaft adapted to engage the first mentioned gear whereby upon engagement of the finger with a perforation in the paper, the interrupted gear will be rotated sufficiently to engage the driven gear, thereby causing a positive rotation of the interrupted gear and finger, and means operated by the finger for

starting the operation of the aforesaid devices.

3. In a copying machine including cutting, feeding and stamping devices, and copying paper, the combination therewith of a constantly driven shaft, a gear on said shaft, said gear meshing with a gear on a second shaft, a sprocket wheel on said second shaft, a feed shaft, a sprocket loosely mounted on the feed shaft, means connecting said sprocket and the first mentioned sprocket, a friction wheel mounted for rotation with the feed shaft sprocket, a pawl fixed on the feed shaft, said pawl being adapted to positively engage the friction wheel, and means operated by the copying paper for causing the engagement of the feed shaft with the sprocket thereon whereby the feed shaft will be rotated.

4. The combination with a copying machine including a feeding device and copying paper, of a finger mounted for rotation above the paper, a pivoted bell crank, one arm of which is in the path of movement of the finger, a second bell crank, one arm of which engages the first mentioned bell crank, a feed shaft, a loosely mounted constantly driven gear on the shaft, a clutch adapted to be operated by the second arm of the second mentioned bell crank, and means in the copy paper for releasing the finger whereby the engagement of the finger with the first bell crank which engages the second bell crank produces the operation of the clutch and the consequent engagement of the feed shaft with the gear thereon.

5. The combination with a copying machine including a feed shaft, of a driven sprocket loosely mounted on the shaft, a grooved wheel mounted for rotation with the sprocket, a pawl on the shaft adapted to engage the grooved wheel, an arm fixed to the shaft, an arm on the pawl for engaging the fixed arm, means for normally holding the pawl out of engagement with the grooved wheel, means for releasing said holding means whereby the pawl will engage the grooved wheel and during the rotation of the pawl the arm on the pawl will engage the arm fixed to the shaft, thereby rotating the shaft.

In testimony whereof, I have hereunto set my hand in presence of two witnesses.

RICHARD BERGER.
